UNITED STATES PATENT OFFICE.

ROBERT W. HANINGTON, OF DENVER, COLORADO.

ORE-COOLER.

1,101,433.

Specification of Letters Patent.

Patented June 23, 1914.

Application filed March 19, 1913. Serial No. 755,358.

To all whom it may concern:

Be it known that I, ROBERT W. HANINGTON, a citizen of the United States, residing in the city and county of Denver and State 5 of Colorado, have invented certain new and useful Improvements in Ore-Coolers; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to improvements in coolers and is adapted particularly for use in cooling ores after the same have been roasted or sintered.

One of the objects of the invention is to 20 increase the available cooling surface for a cooler of a given length and diameter.

Another object of the invention is to provide an apparatus which will agitate the ore to a greater extent than has been customary 25 in previous devices, for the purpose of better exposing the particles to the cooling surfaces.

Still another object of the invention is to provide means for feeding cooling water 30 into the inside of the inner cylinder.

A further object is to so construct and mount the cylinders that the inner one may be drawn out of the outer one whereby access may be had to the operating surfaces of 35 each for purposes of repair and the like.

Other objects will appear hereinafter as I proceed with the description of that embodiment of the invention which for the purposes of the present application, I have illustrated in the accompanying drawings, in which:

Figure 1 is a central vertical longitudinal section taken approximately upon the line 1—1, Fig. 2. Fig. 2 is a cross sectional view upon the line 2—2, Fig. 1, and showing the parts upon a larger scale.

The same reference characters refer to like parts throughout the views.

In the drawings, which form a part of this 50 specification 5 refers to a trough shaped receptacle at the ends of which are built piers 6 and 7. In practice, the trough and piers will probably be made integral and of concrete. At the lower extremity of the receptacle 55 5 is a draw-off pipe 3. At the top of the pier 6 is mounted a short standard 8

which supports a halved bearing 9. Upon the pier 7 is removably secured by means of bolts 10 and nuts 12 a comparatively long standard 13 supporting a halved bearing 14, 60 the parts of which are secured together by bolts 15 and nuts 16.

Rotatably mounted within the bearings 9 and 14 is a hollow shaft 17 closed at one end by a cap 18 in which is a spigot 19 from 65 which water may be drawn to cool the upper part of the shaft and through which any steam that is formed in the upper part of the shaft may be released. Just above the bearing 9 a pulley 20 is attached to the 70 shaft. Any available power source may be employed and power transmitted to the pulley 20 by a belt (not shown). At the opposite extremity of the shaft I attach a rotatable joint 21 to which is connected a pipe 75 22 leading to a source of water supply. Arranged in the pipe 22 is a stop-cock 23 for turning on and off the water and regulating the pressure. That portion of the shaft which is within the cooler is provided at intervals 80 with perforations 24 and with a short nozzle 25 inclined toward the upper end of the shaft. Surrounding the shaft 17 somewhat below its upper bearing is a collar 26 which is set in position upon the shaft 85 by means of a screw bolt 27. The lower end of the collar 26 is provided with a flange 28 to which is secured by bolts 29 a sheet metal plate 30 having an obliquely inclined rim 31. Upon the rim 31 is riveted a conical sheet 90 metal member 32 having at its base a flange 33 which is bent parallel to the axis of the shaft 17. A cylinder 34 is riveted at its upper extremity to the flange 33. At its lower extremity it is riveted to a ring 35 95 which is supported by radial arms 36 and by a collar 37 with which said radial arms are integral, said collar being fastened in position upon the shaft 17 by a screw bolt 38. The lower edge of the cylinder 34 is reinforced by a ring 39 of angle bar metal.

Upon the exterior surface of the cylinder 45 I mount a series of flights 40 of Z-shape. These flights are not continuous from one end of the cylinder to the other but are composed of comparatively short pieces and terminate at some little distance above the lower end of the cylinder. Extending outwardly from the collar 26 are radial arms 41 which at their outer ends are integral with 105 a ring 42. To the inner side of the ring 42 is riveted a frusto-conical member 43 open

at its forward end and reinforced by a ring 44, angular in cross section. To the outer side of the ring 42 is riveted one end of a cylinder 45. At its opposite end the cylinder 45 is supported from the cylinder 34 by angle brackets 4 which are riveted to the cylinder 34 somewhat above the lower end thereof, the ends of said angle brackets being secured by bolts 47 to one flange of a 10 reinforcing ring 48 which is riveted upon the cylinder 45.

On its inner surface, the cylinder 45 carries flights 46 similar in shape to the flights 40 but arranged in staggered relation thereto. 15 If desired, the flights 40 and 46 may both be arranged slightly at an angle to the axes of the cylinders in order to constitute spiral ribs which will assist in feeding the ore from one end to the other. By terminating the flights at some little distance above the lower extremity of the outer cylinder, I permit the ore to slide freely to the bottom and out into an inclined chute 49 which conveys it away from the cooler. The chute is 20 provided on one side with a stop plate 50 to prevent spilling of the ore. 25

At the juncture of the cylinder 45 and the cone shaped member 43, I mount at intervals around the circumference inclined deflecting plates 51 which catch the ore as it is fed down a chute 52 and direct it into the space between the cylinders. Above the cylinders, I arrange a trough 53 which is provided at its lower corners with perforations 30 35 54. Water is delivered to the trough 53 from a pipe 55 in which is a stopcock 56.

Owing to the inclined position of the shaft 17, it is necessary to provide means for holding the shaft against longitudinal movement. 40 For this purpose, I employ a collar 57, fixed in position upon the shaft by means of a set screw 58, the collar 57 abutting against the bearing 14 for retaining the shaft in position.

45 The operation of my improved rotating cooler will be largely apparent from the above disclosure. Rotation of the cylinders should be in the direction of arrow A, Fig. 2. As the ore is fed into the space between the cylinders, it is caught by the flights 46. As each flight proceeds upwardly its carrying capacity is lessened and the ore which it supports gradually rolls off its inner edge, at first falling upon the flight 46 next below. 50 55 But after each flight 46 passes the horizontal position, its ore begins to fall upon the flight 40, next below, and continues to do so until the flight 46 has come to the vertical position directly above the shaft 17. In 60 the meantime, the flight 40 next below, has received this load and has carried it upwardly, the ore being gradually spread out upon the surface of the inner cylinder which is kept cool by the continuous spraying of 65 water upon its inner surface. As the flights

46 proceed from the vertical position directly above the shaft to the three-quarter position, they are entirely free from contact with the ore and their heat is absorbed through conduction by the water upon the outer surface of the cylinder 45. After they pass this three-quarter position, ore again drops upon them from the flights 40 which are given an opportunity to cool. It will, of course, be understood that during rotation of the cylinders, the ore passes constantly downward toward the lower end of the cooler due to the action of gravity and to the spiral arrangement of the flights. 70 75

It is very desirable that means be provided for permitting the cylinders to be readily separated in order that the flights may be renewed and other repairs made from time to time. To this end, I have made the pier 7 short and the standard 13 removable therefrom. When it is necessary to draw out the inner cylinder, I remove nuts 12 and 16 and those upon the bolts 47. Then, I remove the standard 13, bearing 14 and connection with the water pipe 22, loosen the bolts 29, 38 and 58, remove the collar 57 and slide the inner cylinder to the right (Fig. 1) upon the shaft 17. 80 85 90

Although I have herein described the elements of my improved cooler with some particularity it should be understood that such description is merely illustrative of one embodiment that the invention may take, since it is obvious that minor changes in the details of construction may be made without departing from the essentials of my invention as set forth in the appended claims. 95 100

I claim as my invention:

1. In combination, a receptacle, a hollow cylinder mounted to rotate in said receptacle, flights upon the outer surface of said cylinder, a hollow shaft upon which said cylinder is mounted, means for introducing water into said shaft, the latter being provided inside the cylinder with perforations through which water may pass. 110

2. In combination, two rotating cylinders mounted concentrically upon an inclined axis, the inner cylinder extending beyond the outer cylinder at the lower end, the outer cylinder being open at both ends and the inner cylinder being open at the lower end, means for spraying the outer surface of the outer cylinder, means for spraying the inner surface of the inner cylinder, means for feeding material to be cooled to the space between the cylinders at the higher end thereof, and means above the lower extremity of the inner cylinder for conveying away material delivered from the lower end of the space between the cylinders. 115 120 125

3. In a cooler, two rotatable cylinders, mounted concentrically upon a common shaft, the outer of said cylinders being open at one extremity and the attachments of said 130

inner cylinder to the shaft being releasable, the inner cylinder being then readily slideable upon the shaft out of the outer cylinder.

4. In combination, two rotating cylinders mounted concentrically upon an inclined axis, the inner cylinder extending beyond the outer cylinder at the lower end and being open at said end, means for spraying the inner surface of the inner cylinder, means for feeding material to be cooled to the space between the cylinders at the upper end thereof, and means above the lower extremity of the inner cylinder for conveying away material delivered from the lower end of the space between the cylinders.

5. In combination, a receptacle, a hollow cylinder mounted to rotate in said receptacle, a hollow shaft upon which said cylinder is mounted, means for introducing water into said shaft, the latter being provided inside the cylinder with means through which water may pass.

6. A cooler, comprising two cylinders of

different diameters, a hollow shaft upon which one cylinder is mounted concentrically within the other, means for introducing water into said shaft, the latter being provided inside the cylinder with means through which water may pass.

7. A cooler, comprising two cylinders of different diameters, a hollow shaft upon which one cylinder is mounted concentrically within the other, flights upon each of said cylinders extending into the space between the cylinders, the flights upon one cylinder being arranged intermediate the flights upon the other cylinder, and means for introducing water into the hollow shaft, the said shaft being provided inside the cylinder with perforations through which water may pass.

In testimony whereof I affix my signature in presence of two witnesses.

ROBERT W. HANINGTON.
